(57) **CLAIM**

The ornamental design for a cable guide, as shown and described herein.

DESCRIPTION

FIG. 1 is a front top quarter perspective of a cable guide showing the ornamental design of an embodiment;

FIG. 2 is a rear bottom quarter view of the embodiment of FIG. 1;

FIG. 3 is a front view of the embodiment of FIG. 1;

FIG. 4 is a rear view of the embodiment of FIG. 1;

FIG. 5 is a first side view of the embodiment of FIG. 1;

FIG. 6 is a second side view of the embodiment of FIG. 1;

FIG. 7 is a top view of the embodiment of FIG. 1; and,

FIG. 8 is a bottom view of the embodiment of FIG. 1.

The broken line portions of the drawings are for illustrative purposes only and form no part of the claimed design.
